GOLF TEE

Richard Manley Van Valkenburg, Fulton, N. Y.

Application April 1, 1937, Serial No. 134,363

3 Claims. (Cl. 273—33)

The present invention relates to new and useful improvements in golf tees and has for one of its important objects to provide, in a manner as hereinafter set forth, an article of this character embodying novel means for firmly supporting the ball in elevated position when in use.

Another important object of the invention is to provide a golf tee which, when not in use, will occupy a minimum of space.

Still another important object of the invention is to provide a golf tee of the aforementioned character which may carry considerable advertising matter.

Other objects of the invention are to provide a golf tee of the character described which will be comparatively simple in construction, strong, durable, which may be left on the ground without danger to other golfers, and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a top plan view of a golf tee constructed in accordance with the present invention.

Figure 2 is a vertical sectional view through the invention, showing the device in use.

Figure 3 is a sectional view, taken substantially on the line 3—3 of Fig. 1.

Figure 4 is a bottom plan view of the tee.

Referring now to the drawing in detail, it will be seen that the embodiment of the invention which has been illustrated comprises a laminated disk 1 of suitable material, preferably paper or cardboard. Formed in the upper portion of the laminated disk 1 are incisions 2 defining supporting tabs 3 which are adapted to be lifted to substantially the position shown in Fig. 2 of the drawing when the tee is to be used. The tabs 3 swing at their outer ends, as at 4. The adjacent inner ends of the tabs 3 have formed therein arcuate recesses 5 for the reception of a golf ball, as at 7. When the tabs 3 are in closed position, as illustrated to advantage in Fig. 3 of the drawing, the recesses 5 also facilitate the insertion of a finger or thumb nail for the purpose of lifting said tabs.

Struck from the tabs 3 are integral supports 6 which are adapted to hinge or swing on said tabs adjacent the free ends thereof, as best seen in Fig. 2 of the drawing. The supports 6 are pref-

erably of substantially the shape shown to advantage in Fig. 1 of the drawing. Any suitable advertising or other matter may be placed on either or both sides of the laminated disk 1. Also, the laminated member 1 may be of any suitable shape other than circular.

It is thought that the manner of using the tee will be readily apparent from a consideration of the foregoing. When the tee is to be used, the tabs 3 are raised by inserting a finger or thumb nail beneath the free inner ends thereof in the arcuate recesses 5. After the tabs 3 are thus lifted the supporting braces 6 are pressed inwardly with the free lower ends thereof resting on the lower portion of the laminated disk 1 in the recesses left by said tabs 3. The ball 7 may then be set in the arcuate recesses 5 in a manner to be firmly supported between the oppositely inclined tabs 3. The construction and arrangement is such that a player may carry a large number of the tees without inconvenience and, if desired, discard each tee after it has been used once. Also, the tee may be left on the ground without fear of injury to other golfers or animals. Still further, each time that the tee is used the advertising matter thereon will come under the observation of the golfer.

It is thought that the many advantages of a golf tee constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A golf tee comprising a laminated member having incisions in its upper portion defining liftable tabs adapted to support a golf ball in elevated position on said member, said incisions intersecting and providing a slotted opening and such point of intersection forming a common fingernail receiving opening for lifting the respective tabs and integral braces struck from the tabs and extending vertically with its lower end resting on the member when said tabs are in lifted position to support the tabs in upwardly extended position.

2. A golf tee comprising a laminated member having incisions in its upper portion defining liftable tabs adapted to support a golf ball in elevated position on said member, said incisions intersecting and providing a slotted opening and such point of intersection forming a common

fingernail receiving opening for lifting the respective tabs, said slotted opening further having arcuate edges to provide arcuate recesses in their free ends when the tabs are lifted for the 5 reception of the ball, and integral braces struck from the tabs and extending vertically with its lower end resting on the member for supporting said tabs in lifted position.

3. A golf tee of the character described comprising a laminated disk having a pair of circular incisions in its upper portion, said incision terminating at one side of the circle in an unsevered edge and defining a pair of opposed, complementary, liftable tabs adapted to be swung up-

wardly and outwardly from their outer ends for supporting a golf ball in elevated position on said disk, said incisions further intersecting at one edge and provided at said edge with a slotted opening forming a common fingernail receiving opening for lifting the respective tabs, said slotted opening further having arcuate edges to provide arcuate recesses in their free ends when the shafts are lifted to facilitate lifting said tabs and for the reception of the ball, and integral braces struck from the tabs and extending vertically with its lower end resting on the disk for supporting said tabs in lifted position. 5 10
